UNITED STATES PATENT OFFICE.

ALOYSIUS S. TERHAAR, OF SAN DIEGO, CALIFORNIA.

SAFETY APPLIANCE FOR SHIPS.

1,227,093.

Specification of Letters Patent. Patented May 22, 1917.

Application filed March 30, 1916. Serial No. 87,670.

To all whom it may concern:

Be it known that I, ALOYSIUS S. TERHAAR, a citizen of the United States, residing in the city of San Diego, in the county of San Diego and State of California, have invented a new and useful Safety Appliance for Ships, of which the following is a specification.

My invention relates to safety devices for ships whereby the bow of the ship may be suddenly turned independently of the rudder or forward driving propellers, so as to avoid collision.

My objects are to provide such a device capable of being mounted in the keel of a ship adapted for its reception, that may be governed by the pilot, whereby the ship may be turned abruptly to the right or left or completely around so as to avoid collision in a fog where objects cannot be discerned at any considerable distance or in a channel where plenty of room is not available; that will assist in docking a ship by driving the bow sidewise; that will assist in holding the course at sea in a storm, by driving the bow against the wind; that will enable a ship to come in close on the windward side of a wreck in rescue work and by driving the bow away from the wreck, prevent its being blown on the wrecked ship; that will enable a ship to veer sharply when a submerged obstacle is encountered; that will enable a ship to continue her trip in the event that the rudder becomes disabled; to provide watertight bearings in said device; to provide a transmission operated from the inside of the ship, that shall be incased in beams which carry a shaft upon which a propeller is mounted; to provide said beams of such shape that the resistance of the water shall be reduced to the minimum; and in general to provide a simple easily operated device of such simplicity that the liability of getting out of working order is reduced to the minimum. Other objects will appear as the description progresses.

The preferred form of the invention is illustrated by the accompanying drawings which are for illustrative purposes and are therefore not drawn to scale; it being understood that I do not confine myself to the particular embodiment herein shown but to that within the scope of what hereinafter is claimed; divers changes in the form size and

minor details of the structure may be made without departing from the spirit of the invention.

Similar reference characters refer to like parts throughout the several views.

Figure 1 is a representation of an elevation of a ship having my device installed in the forward part of the keel; the wires W being broken away; Fig. 2 an elevation of the part of Fig. 1 cut out by the line A—B, drawn to an enlarged scale; Fig. 3 a plan view of Fig. 2 on the line C—D of Fig. 2; Fig. 4 a vertical cross section on the line E—F of Fig. 2; Fig. 5 a plan view of the mechanism removed from the tube 10, drawn to an enlarged scale, one of the beams 1 being shown in section to disclose the manner of mounting the shaft 3 and the gears 6 and the disposition of the oil holes 7 and 8 and the thimble 9. Fig. 6 an elevation of a cross section on the line G—H of Fig. 5 looking in the direction of the arrow, part of one propeller blade 13 being broken away; Fig. 7 an elevation of a cross section on the line I—J of Fig. 5; and Fig. 8 an elevation of one of the beams 1 looking at the sharp edge, the thimble 9, the shaft 3 and the gear 6 being removed.

Referring to Figs. 5, 6, 7 and 8 in detail—

1, 1 are beams, wedge shaped in cross section, having flanges 12 on the ends thereof by which they can be riveted to the tube 10 as shown in Figs. 1, 2, 3, and 4; 7 and 8 are oil holes; 9, 9 are thimbles mounted watertight in said beams; 3 is a shaft journaled in said beams; 6, 6 are gears mounted on said shaft; c, c are chains mounted on said gears and on gears mounted on the drive shaft of a motor M disposed in the ship as shown by Figs. 2 and 3; 4, 4 are chambers for said chains within said beams; 13 is a screw propeller rigidly mounted on said shaft 3; and W denotes transmission wires from the motor M to a station on the bridge of the ship.

The mechanism is assembled as follows: The propeller 13 is keyed on the shaft 3; the shaft is thrust into the holes in the bosses; the gears 6 are slipped on the shaft and keyed on; the thimbles 9 are inserted and the flanges bolted or otherwise secured and brazed or otherwise sealed watertight and the flanges 12 of the beams 1 are bolted or riveted to the drum 10 and the bolt heads sealed watertight; the drum 10 is mounted

in the keel of the ship which has been previously adapted for its reception and bolted to the ship as shown in Figs. 2, 3 and 4, the bolt heads being sealed water tight. The 5 drum and the part of the ship which comes next to it have holes coinciding with the chambers 4 and the oil holes 7 and 8. After mounting in the above manner the chains are thrust into the chambers 4 until they become engaged with the teeth of the gears 6 after which the shaft 3 is revolved and thereby brings the chains out at the openings of 10 the return portions of the chambers. The chains are then mounted on a motor M which has been previously installed in the ship. The motor is connected with the engine room from which it receives the current and with the bridge B from which it is operated by the pilot. The pilot controls the device 15 by throwing the current on or off as the case may require, and by starting the motor forward or backward, since he has the two currents at his disposal that will run the motor either forward or backward, which is so well understood that it needs no explanation here.

20 In use the device is operated as follows:

When a submerged obstacle is encountered on the right hand side of the ship, the propeller is actuated backward by switching on the proper current and the bow is veered sharply thereby to the left. This not only moves the ship away from the obstacle but forces a volume of water through the tube 10 from left to right and, if the obstacle be 25 movable, forces it away from the ship. If the obstacle be immovable the force of the volume of rushing water through the tube 10, strikes the obstacle and reacts on the ship and helps drive the ship away from it. 30 This feature of the rushing water is especially advantageous when two ships meet head on in a fog. If both ships are equipped with my device, the pilots switch the proper currents to revolve their respective motors 35 in the proper direction and the volumes of water which are forced through the respective tubes 10 react on each other and assist the normal action of the propellers 13 and thereby accomplish the turning more rapidly. 40 In assisting a ship to dock, the bow is driven sidewise by the action of the propeller 13 and thereby swung against the dock. By installing the device at both ends of the ship, the ship may be driven sidewise 45 against the dock. In the event that the ship's rudder becomes disabled the device 50 may be used as a steering means, by the pilot switching the proper currents on and off as the case may require, thereby turning 55 the bow to the right or to the left. In turning 60 completely around the propeller 13 is actuated in the desired direction until the turn is accomplished. In holding a course at sea in a storm the propeller 13 is actuated in 65 the proper direction to drive the bow against

the adverse wind and thereby helps to counteract the effect of the wind. In rescue work on the high sea the ship may be brought along side the wrecked ship on the windward side and by revolving the propeller 13 70 in the proper direction, the rescue ship may be kept from being blown onto the wrecked ship. It may be used to advantage on revenue cutters; on boats of the Life Saving Service and in all conditions where mobile 75 ability and absolute control is required at all times.

Although I deem an electric motor preferable as an actuating means, yet I do not confine myself to such means for the device may be operated by any other means producing 80 rotary motion.

Storage batteries may be used with an electric motor and be ready for instant starting after which a signal to the engineer would 85 notify him to cut in the current from the dynamos in the engine room.

Having thus described my invention, what I claim as new and desire to secure by Letters Patent of the United States is:

1. In a safety appliance for ships, of the class described, in combination; two parallel horizontally disposed beams adapted to be mounted in a tube mounted in the keel of a ship; a horizontally disposed shaft journaled in said beams; a propeller mounted on said shaft between said beams; and gears mounted on said shaft and disposed within 90 said beams; for the purposes set forth.

2. In a safety appliance of the class described, in combination; two horizontally disposed beams adapted to be mounted in a tube, said tube being mounted in the keel of a ship; a propeller mounted on a shaft journaled in said beams; gears mounted on said shaft and disposed within said beams; and chains mounted upon said gears and disposed longitudinally within said beams; for the 95 purposes set forth.

3. In a safety appliance of the class described; the combination of two horizontally disposed beams mounted in a tube mounted in the keel of a ship transversely thereof; a horizontally disposed shaft journaled in said beams and having a propeller mounted thereon between said beams; gears mounted on said shaft within said beams; chains disposed longitudinally within said beams and mounted on said gears; for the purposes set forth.

4. A safety appliance of the class described comprising a tube mounted transversely in the keel of a ship; two horizontally disposed beams mounted in said tube longitudinally of the ship; a propeller mounted 125 on a shaft journaled in said beams; gears disposed within said beams and mounted on said shaft; chains disposed longitudinally within said beams and mounted on said gears, said chains extending into the ship 130

and being mounted on an actuating means disposed within said ship; for the purpose of turning said ship's bow.

5. A safety appliance for ships, comprising a tube mounted transversely in the keel of a ship; two horizontally disposed wedge beams having their ends secured to the sides of said tube and having longitudinally disposed chambers therein adapted to receive 5 chains; gears mounted on a horizontally disposed shaft within said beams; chains disposed within said chambers and mounted 10 on said gears, said chains being connected

with an actuating means disposed within said ship; and a propeller mounted on said 15 shaft between said beams; for the purpose of guiding said ship.

In testimony that I claim the foregoing as my own, I have hereunto affixed my signature in the presence of two subscribing 20 witnesses.

ALOYSIUS S. TERHAAR.
